CALCULATING MACHINES

Alfons Boothby, Wilhelmshaven, Germany, assignor to
Olympia Werke AG, Wilhelmshaven, Germany

Filed Oct. 18, 1967, Ser. No. 9,041

Term of patent 14 years

(Cl. D64—11)

FIG. 1

FIG. 3

FIG. 2

FIG. 1 is a perspective front view of a calculating machine showing my new design;

FIG. 2 is a perspective rear view; and

FIG. 3 is a perspective side view.

The essential features of the design reside in the portions shown in solid lines; conventional keys being shown in broken lines in all the views.

I claim:

The ornamental design for a calculating machine, substantially as shown and described.
